UNITED STATES PATENT OFFICE.

CHESTER McNEIL, OF CHICAGO, ILLINOIS, ASSIGNOR TO UNION SPECIAL MACHINE COMPANY, OF CHICAGO, ILLINOIS, A CORPORATION OF ILLINOIS.

FILLED-BAG-SEWING APPARATUS

1,170,303.

Specification of Letters Patent.

Patented Feb. 1, 1916.

Application filed January 6, 1910. Serial No. 536,669.

To all whom it may concern:

Be it known that I, CHESTER McNEIL, a citizen of the United States, residing at Chicago, in the county of Cook, State of Illinois, have invented certain new and useful Improvements in Filled-Bag-Sewing Apparatus, of which the following is a description, reference being had to the accompanying drawing and to the letters and figures of reference marked thereon.

My invention relates to an improvement in apparatus for feeding and sewing filled bags. It has been designed especially for use in connection with the Union Special type of such apparatus, as illustrated generically in the patent to Bigelow, No. 875,314, of December 31st, 1907, and more specifically in that to Foster, No. 875,339, of December 31st, 1907, although not restricted to such type of apparatus. In such type of apparatus, it is usual to employ a device for cutting or severing the chain of stitching between two successive bags, after the sewing up of the mouth of the filled bag has been performed. These cutting or severing devices are of various types, which are well known in the art. It has been found in practice, that in order to make the cutting device sure in its action, the chain of stitching should preferably be in a taut condition when operated on, and it is the object of my invention to provide means for insuring that at the time the cutting device, whether of the shear type or cutter and anvil type, is operated, the chain of stitching shall be in taut condition and not sagged.

To this end, my invention generically provides for a means whereby when the bag mouth has been sewed, the position of the bag will be automatically shifted, so as to stretch the chain taut in the path of the cutting device; and secondarily, it includes means whereby as the conveyer belt feeds along the bag, the latter after the sewing has been accomplished will tilt or topple or move along with its mouth in advance of its base, thus tightening the chain.

Finally, the invention consists in the matters hereinafter described and referred to in the appended claims.

The invention is illustrated in the accompanying drawings, in which,—

Figure 1 is a perspective view of a filled bag sewing apparatus of the Union Special

type, embodying my invention; and Fig. 2 is a front view, illustrating my invention in detail; Fig. 3 is a modification of Fig. 2; Fig. 4 is a detail view of the tilt board F; Fig. 5 is a detail showing in side elevation the end of the work support, the presser foot and the cutting mechanism for severing the threads between the filled bags.

In these drawings, the supporting framework A, sewing machine mechanism B, conveyer belt C, and table D over which it runs, are of the usual and well known construction. The cutting or severing device E consists of a movable member 1 and a fixed member 2, said fixed member being held by a clamping screw 3. The movable member 4 is mounted on a lever 4 pivoted to a bracket 5 and this lever is oscillated by a link 6, which is connected to a part of the operating mechanism of the sewing machine. The presser foot P holds the mouth of the bag 7 against the work support W.

As above stated, it sometimes happens that when the sewing has been accomplished, and the chain of stitching to the succeeding bag is being formed, and the feed of the sewing machine has ceased to act on the bag mouth, the chain will sag and not be presented properly to the cutting device E. I have provided a remedy for this, by arranging a means to draw the chain taut and keep it taut, while the cutting action is being performed. As herein illustrated, this means consists, as shown in Fig. 2, in providing between the upper layer of the conveyer belt C, and its supporting table D, a tilt board F, which may be formed with or separate from the table D. It inclines upwardly, as shown at a and then inclines downwardly, as shown at b, this inclined portion b being so arranged with respect to the stitching mechanism of the sewing machine, that when the bag mouth has been sewed and the chain begins its forming, the bag will be tilted in the direction of feed, thus making the chain taut and bringing it also directly in the path of the cutting device. As shown in Fig. 3, the table D may itself be inclined, as at b', from a point beneath the stitching mechanism, down toward its end, thus accomplishing the same result. It will also be understood that the same result may be accomplished in other ways; for example, the speed of the bag as a whole

might be accelerated slightly after the stitching has been performed, whereas in the forms above illustrated, the effect of the tilting of the bag is by the action of gravity 5 to accelerate the speed of the upper portion of the bag, for an instant, or to carry the same through a greater distance than the base.

The guide rails G and G' are employed 10 to guide the bags, the one G' in rear of the stitch-forming mechanism being arranged in a different vertical plane from the rail G and prevents toppling over of the bag, when it has been tilted.

15 Having thus described my invention, what I claim as new and desire to secure by Letters Patent, is:—

1. A filled bag sewing apparatus including in combination stitch forming mechanism, carrying means for supporting and feeding a filled bag to the stitch forming mechanism, means located in rear of the stitch forming mechanism for severing the chain of stitches between the filled closed 20 bag and the stitch forming mechanism, and means for rendering taut the chain of stitches for the action of the severing means.

2. A filled bag sewing apparatus including in combination stitch forming mechanism, a conveyer located beneath the stitch-forming mechanism and operating to present a filled bag to the stitch forming mechanism, means located in rear of the stitch forming mechanism for severing the chain 25 of stitches between the closed bag and the stitching mechanism, and means for shifting the point of contact of the chain of stitches with the filled bag relative to the stitching mechanism for rendering said 30 chain of stitches taut for the action of the severing means.

3. A filled bag sewing apparatus including in combination stitch forming mechanism, a conveyer located beneath the stitch-forming mechanism and operating to present a filled bag to the stitch forming mechanism, means for severing the chain of 35 stitches between the closed bag and the stitching mechanism, and means for shifting the position of the bag for rendering taut the chain of stitches between the closed bag and the stitching mechanism for the operation of the severing means.

4. A filled bag sewing apparatus including in combination stitching mechanism, a conveyer for presenting a filled bag to the stitching mechanism, means for severing the chain of stitches between the closed bag 40 and the stitching mechanism, and means for tilting the bag relative to the stitching mechanism after the filled bag is closed for rendering the chain of stitches taut between the bag and the stitching mechanism for the operation of the severing means.

5. A filled bag sewing apparatus includ-

ing in combination stitching mechanism, a conveyer for presenting a filled bag to the stitching mechanism, means for severing the chain of stitches between the closed bag and the stitching mechanism, means for tilting the bag relative to the stitching mechanism after the filled bag is closed for rendering the chain of stitches taut between the bag and the stitching mechanism for the operation of the severing means, and means 70 located at one side of the bag for preventing the same from toppling over.

6. A filled bag sewing apparatus including in combination stitching mechanism, a conveyer for presenting a filled bag to the stitching mechanism, means for severing the chain of stitches between the closed bag and the stitching mechanism, and means for tilting the bag relative to the stitching mechanism after the filled bag is closed for rendering the chain of stitches taut between the bag and the stitching mechanism for the operation of the severing means, said tilting 75 of the bag being in the direction of the travel of the conveyer.

7. A filled bag sewing apparatus including in combination a sewing head having sewing means and a feeding mechanism, a conveyer for presenting a filled bag to the sewing mechanism, a support for the conveyer, and means located intermediate the ends of the support for tilting the bag after the same is closed to render the chain of 80 stitches between the bag and the stitching 85 mechanism taut.

8. A filled bag sewing apparatus including in combination a sewing head having sewing means and a feeding mechanism, a conveyer for presenting a filled bag to the sewing mechanism, a support for the conveyer, means located intermediate the ends of the support for tilting the bag after the same is closed to render the chain of 90 stitches between the bag and the stitching 95 mechanism taut, and means located in rear of the stitching mechanism whereby said taut chain of stitches may be severed.

9. A filled bag sewing apparatus including in combination stitching mechanism, a conveyer located beneath the stitch-forming 100 mechanism and operating to present a filled bag to the stitching mechanism, means for severing the chain of stitches between the closed bag and the stitching mechanism, and means for shifting the position of the top 105 of the bag relative to the stitching mechanism after the bag is closed for rendering taut the chain of stitches between the bag 110 and the stitching mechanism for the operation of the severing means.

10. A filled bag sewing apparatus including in combination stitching mechanism, a conveyer for presenting a filled bag to the stitching mechanism, means for shifting the bag from an upright to an inclined position 115

after the bag has been closed to render the chain of stitches between the bag and stitching mechanism taut.

11. A filled bag sewing apparatus including in combination stitching mechanism, a conveyer for presenting a filled bag to the stitching mechanism, means for shifting the bag from an upright to an inclined position after the bag has been closed to render the chain of stitches between the bag and stitching mechanism taut, and means adapted to sever the chain of taut stitches between the closed bag and the stitching mechanism.

12. A filled bag sewing apparatus including in combination a conveyer belt, a table over which said belt is moved, a stitching mechanism located above said conveyer belt, said table having an irregular surface at a point substantially beneath the stitching mechanism, whereby the position of the bag on the conveyer belt is automatically shifted to tighten the chain of stitches between the closed bag and the stitching mechanism subsequent to the closing of the bag.

13. A filled bag sewing apparatus including in combination a conveyer belt, a table over which said belt is moved, a stitching mechanism located above said conveyer belt, said table having an irregular surface at a point substantially beneath the stitching mechanism, whereby the position of the bag

on the conveyer belt is automatically shifted to tighten the chain of stitches between the closed bag and the stitching mechanism subsequent to the closing of the bag, and means for severing the taut chain of stitches in rear of the stitching mechanism.

14. A filled bag sewing apparatus including in combination stitching mechanism, a cutting device for severing the chain of stitches between the stitching mechanism and the closed bag, a conveyer belt for presenting the filled bag to the stitching mechanism, a table over which said belt moves, a tilting board interposed between the table and the conveyer belt, and having a surface inclined downwardly in the direction of the travel of the belt, said surface being located substantially beneath the stitching mechanism, whereby, when the bag leaves the stitching mechanism and is closed, the same will be tilted so as to render the stitches between the closed bag and the stitching mechanism taut for the operation of the cutting device.

In testimony whereof I affix my signature, in presence of two witnesses.

CHESTER McNEIL.
